DESIGN FOR A MOUNTING FOR A HAND TELEPHONE

Ralph H. Ricker, Newark, N. J., assignor to Bell
Telephone Laboratories, Incorporated, New
York, N. Y., a corporation of New York

Application September 11, 1946, Serial No. 133,251

Term of patent 14 years

(Cl. D26—14)

To all whom it may concern:

Be it known that I, Ralph H. Ricker, a citizen
of the United States, residing at Newark, in the
county of Essex and State of New Jersey, have
invented a new, original, and ornamental Design
for a Mounting for a Hand Telephone, of which
the following is a specification, reference being
had to the accompanying drawing, forming a part
thereof.

In the drawing:

Fig. 1 is a perspective view of a mounting for
a hand telephone, showing my new design;

Figs. 2 and 3 are side and front elevational
views respectively of the mounting; and

Fig. 4 is a bottom plan view of the mounting.
The dotted line disclosure is for illustrative pur-
poses only.

What I claim is:

The ornamental design for a mounting for a
hand telephone, as shown and described.

RALPH H. RICKER.
